UNITED STATES PATENT OFFICE.

RALPH R. JANES, OF BROOKLYN, NEW YORK, ASSIGNOR TO STANDARD KNITTING MILLS COMPANY, A CORPORATION OF NEW YORK.

METHOD OF MAKING KNITTED UNDERGARMENTS.

1,284,899.

Specification of Letters Patent. Patented Nov. 12, 1918.

Application filed December 1, 1914. Serial No. 874,966.

To all whom it may concern:

Be it known that I, RALPH R. JANES, a citizen of the United States, residing in the borough of Brooklyn, in the city and State 5 of New York, have invented certain new and useful Improvements in Methods of Making Knitted Undergarments, of which the following is a full, clear, and complete description.

10 My invention relates to knitted garments, and more especially to knitted undergarments, or garments of like nature, and has for its object the provision of a method of making such garments which will be rapid 15 and inexpensive and which will produce garments pleasing in appearance and comfortable in use.

It is well known that knitted fabric stretches very much more easily in the direction transverse to the ribbing than it does 20 in the direction of the ribbing. In knitted undergarments of the simplest form, the ribbing runs in a generally vertical direction; and in the shoulder portions runs from 25 front to back, or substantially parallel with the sleeve openings. There is, therefore, little resistance to the tendency of the shoulders of the garment to stretch in the direction transverse to the sleeve opening, 30 and as a result the seam at the sleeve opening is apt to fall down onto the arm of the wearer. This causes discomfort and also, in effect, increases the length of the sleeves. In order to avoid this, the common expedient 35 is to insert along the top of the shoulder from the neck opening to the sleeve opening, a piece of fabric in which the ribbing runs at right angles to the ribbing of the remainder of the body portion of the garment. 40 Thus the ribbing runs in the direction of the tension along the top of the shoulder, and the stretching is, therefore, materially reduced. But this method has the disadvantage of employing an increased number of 45 seams, thus increasing the labor and cost of manufacture, and detracting from the appearance and comfort of the garment.

By my improved method I eliminate the objectionable stretching along the shoulder 50 and at the same time produce an attractive and entirely comfortable garment in a very rapid and inexpensive manner, an important feature of my method being the reinforcement of the seam along the top of the shoul-

der from the neck opening to the sleeve opening with a tape of non-elastic material.

In the drawing, Figure 1 illustrates the garment in the course of manufacture;

Fig. 2 is a front view of the completed garment;

Fig. 3 is a plan view thereof; and

Fig. 4 is a detail view showing the method of reinforcing the shoulder seam of the garment.

The piece of knitted tube shown in Fig. 1 is cut to the desired length and at one of the upper corners a segmental piece of material is cut out at 2, 3, to form the neck opening of the garment. The tube is then slit at 3, 4, to provide the usual breast opening and is cut through at 5, 6, to form the sleeve openings. When the tube is now reversed, as shown in Fig. 2, it is provided with the neck opening 2, 3, 2, the breast opening 3, 4, and the sleeve openings 5, 6, 75 and all that is necessary to complete it is to sew on the sleeves 7, 7, sew the shoulder seams 2, 5, and 2, 5, and add the desired trimmings, buttons, etc.

If the shoulder seams 2, 5 and 2, 5 were 80 sewed in the ordinary way, there would occur the objectionable stretching above referred to, due to the fact that the direction of the ribbing at this point is transverse to the direction of the tension applied. But I 85 have found that this stretching can be eliminated by reinforcing the shoulder seams 2, 5 with a tape of inelastic material. These seams are sewed by a multiple needle sewing machine the lines of stitches being indicated at 8, 9 and 10 Fig. 4, and as they are being sewed the tape is run in, and is thus penetrated, sewed down and over-lapped or covered by the stitching of the seam as indicated in Fig. 4. A suitable guide for the 90 tape may be attached to the throat plate, presser foot, or any other suitable part of the machine. This produces a seam which is substantially non-elastic and at the same time attractive in appearance and comfortable to the wearer. This seam also adds strength to the garment and thus causes it to wear longer than it otherwise would.

The advantages of my improved method are evident. In the first place, the objectionable stretching of the shoulders is entirely eliminated. In the second place, the step of cutting the neck, breast and sleeve

openings is a very simple and inexpensive one, since it can be done by a machine in a single operation. Those methods which include the insertion of an extra piece of fabric along the top of the shoulder generally require some hand cutting which, of course, is slow and expensive. Also, the sewing which is required to complete my garment is reduced to a minimum, no extra time being required to reinforce the shoulder seams. In other methods which seek to accomplish the results accomplished by me, there is at least one additional seam on each shoulder, requiring additional sewing and, consequently, additional expense. Also, the elimination by me of all extra and unnecessary seams makes the garment much more comfortable.

I do not wish to limit myself to the particular method of reinforcing the shoulder seams above described, nor do I wish to limit the use of the reinforced seam to any particular form of garment nor to any particular location in a garment, for obviously many different methods of reinforcing seams and many different uses for such

seams may be devised by those skilled in the art without departing from the spirit of my invention.

What I claim is:

The method of making a garment which consists in cutting a tube of knitted material to the desired length, cutting a segmental piece from one of the upper corners of the tube to form a neck opening, cutting a slit downwardly from the lower point of said opening to form the chest opening, cutting a slit extending downwardly from substantially the center of the top edge of the tube to form sleeve openings all in one operation; then, reversing the tube, and sewing together the upper, front and back edges of the tube between the neck opening and the sleeve openings, and at the same operation sewing to the seams so formed a reinforcing tape of non-elastic material, by penetrating and overlapping said tape by the same stitches which form the seams.

RALPH R. JANES.
